UNITED STATES PATENT OFFICE.

PHILIP A. FISCHER, OF NEW YORK, N. Y.

GARTER.

Application filed November 14, 1925. Serial No. 69,026.

This invention is a garter of the band type, in which the garter is held in operative position by the frictional inter-engagement between the parts of the garter, and 5 between the garter and the limb of the wearer. My co-pending application, filed of even date herewith, Serial No. 69,025, is for a somewhat similar type garter, but embodying different structural features.

10 The garter of this invention is made of flexible material having a rather rough surface for increasing the frictional grip between the inter-engaged parts of the garter, and between the parts of the garter and the 15 limb or clothing of the wearer. Wool is the preferred material because of its rough surface, and it is preferably knitted or woven in such a way as to produce a rough rather than a smooth surface; the wool or other 20 material may have corrugations or ribs, preferably extending transversely of the garter, for increasing the frictional grip.

Structurally, one end of the garter of this invention is formed into a relatively 25 small tubular portion, constricted to such an extent that the other or free end of the garter has to be rolled or folded and forced through the tubular parts to overcome its restrictive effect. The result of this tight 30 fit is that the tubular part imposes a very considerable holding effect on the free end of the garter, the free end, however, being slidably through the tubular part for adjusting the garter when sufficient force is applied.

In order that the free end of the garter be held securely when the garter is in operative position, such free end is tucked under the body of the garter and held between it 40 and the clothing of the wearer. The combined effect of the tubular portion and the tucking in on the free end of the garter is to hold such free end with all necessary security so that the garter imposes a sufficient 45 restrictive force around the leg of the wearer for holding up the hosiery. The free end, however, may be held otherwise than by tucking, as will appear.

A garter of this type may, if desired, be 50 sewed or otherwise secured to the hosiery

with a degree of permanency. It also may be provided with hosiery engaging means of a known type. Both of these variations are, however, optional.

The garters are all slidably adjusted by 55 sliding the free end of the garter through the constricted tube, and thereafter further securing the free end in any of the several ways shown.

Referring now to the drawings illustrating more specifically several embodiments 60 of the invention,

Fig. 1 is a perspective view of one form of the garter in operative position;

Fig. 2 shows a modification in operative 65 position;

Fig. 3 shows another modification;

Fig. 4 shows a modification including the 70 hosiery engaging member;

Fig. 5 shows a modified way of forming the tubular part.

Referring now to these drawings, in which similar reference characters indicate similar parts, 1 indicates an elongated member of flexible material having a rough surface, preferably of wool, knitted or woven, and having, if desired, transversely extending corrugations 2 for increasing the rough surface of the garter.

The tubular part 3 of the garter is formed by sewing together or otherwise securing the upper and lower edges 4 and 5 of member 1, the stitches being indicated at 6. The axis of the tubular part 3 extends substantially lengthwise of the elongated member 75

1. The tubular part 3 is of such a size that the other or free end 7 of the garter can only be forced through it with some difficulty, the resultant tight fit of the end of the garter in the tubular part 3 acting to 80

hold the free end 7 of the garter with a fairly tight fit, but hardly sufficient for practical purposes. The holding effect of the garter is completed by additionally holding the free end 7. In Fig. 1 this free end is tucked under the body 1 of the garter and is thus subject to the clamping, frictional effect of the body of the garter on one side, and the limb or clothing of the wearer on the other. The extreme end of the garter may be turned 95 100

over and sewed, as at 8, thereby forming a shoulder 8' which may engage over the top edge 4 of the garter.

The modification in Fig. 2 is provided with the tubular portion 3 as in Fig. 1, and is also provided with a restricted opening 10 of a size such that the free end 7 has to be forced through it, thus imposing an additional frictional holding effect on the garter. After being threaded through the opening 10 the end 11 of the garter is further held between the body of the garter and the limb of the wearer, as shown, and so is subject to frictional forces on both sides as described in connection with Fig. 1.

Any of the types of garter illustrated in the drawings may, as indicated in Fig. 2, be attached to the hosiery 12 with a degree of permanency by stitches 13. Fig. 2 also shows that the upper part 14 of the hosiery may be turned down to conceal the garter, as is customary with golf stockings.

Referring now to Fig. 3, this form has the usual tubular part 3, and also a plurality of restricted openings 15, of a size to impose a frictional holding effect on the free end 7 of the garter, such free end being passed successively through the tubular part and through the holes 15. With this form the free end 7 is held very securely, and does not need to be tucked under the body of the garter.

Fig. 4 shows a modification where the body 1 of the garter is provided with a depending hosiery engaging member 16 of known design.

In Fig. 5, the tubular part of the garter is formed by sewing a strip 20 to one end of the garter by upper and lower rows of stitches 21 and 22, leaving the ends 23 intermediate the stitches free, so that they may be lifted away from the body 1 of the garter. The free end of the garter may thus be threaded under the strip 20, thus to form a tubular constricting part acting in practically the same way as the tubular part 3 already described.

The several types of garters according to this invention may be used on men's, women's and children's hosiery, being more particularly useful with golf hosiery. Decorative ribbons or rosettes could be used as desired. While the invention has been illustrated in some detail, it should be understood that it may be carried out in other ways, and accordingly is not to be restricted to the precise details illustrated.

I claim as my invention:

1. A garter of the band type comprising a substantially flat elongated member one end of which is formed into a tubular portion the axis of which extends lengthwise of the elongated member, the other end of the garter being adjustably slidable through

the tubular portion, the tubular portion being constricted for imposing a frictional holding force for a substantial distance along that end of the garter passing therethrough.

2. A garter of the band type comprising a substantially flat elongated member one end of which is formed into a tubular portion the axis of which extends lengthwise of the elongated member, the other end of the garter being threadable through the tubular portion, the tubular portion being constricted for imposing a frictional holding force for a substantial distance along that end of the garter passing therethrough, the end of the garter, after passing through the tubular portion being further frictionally held by being positioned between the elongated member and the limb of the wearer.

3. A garter of the band type comprising an elongated member one end of which has a tubular part formed thereon by securing together the side edges of the member at one end thereof, the tubular part thus formed being adapted to receive the other end of the garter with a relatively tight fit.

4. A garter of the band type comprising an elongated member one end of which is formed into a tubular portion and which is provided with a constricted opening, the other end of the member passing successively through the tubular portion and the constricted opening.

5. A garter of the band type comprising an elongated member one end of which is formed into a tubular portion and which is provided with a constricted opening, the other end of the member passing successively through the tubular portion and the constricted opening and thereafter being held between the body part of the garter and the limb of the wearer.

6. A garter of the band type comprising an elongated substantially flat member one end of which is formed into a tubular portion, the axis of which extends lengthwise of the elongated member, the tubular portion being adapted to receive the other end of the garter and impose a frictional restraining force thereon, the garter being made of a material having a rough surface for increasing the frictional grip of the parts of the garter.

7. A garter of the band type comprising an elongated member one end of which is formed into a tubular portion, by securing the side edges of the elongated member to each other the other end of the elongated member being threaded through the tubular portion, and thereafter is held between the body of the garter and the limb of the wearer, for frictionally holding the garter in operative position, the garter being made

of a material having transversely extending ribs thereon for increasing the frictional grip of the garter.

8. A garter of the band type comprising an elongated member, which, at one end, is formed into a tubular portion made of the same material as the said member, and the axis of which extends substantially lengthwise of the elongated member, the tubular

portion being adapted to receive the other 10 end of the garter and impose a frictional restraining force thereon, the garter being made of wool having transversely extending ribs formed therein for increasing the frictional grip of the parts of the garter. 15

In testimony whereof I affix my signature.

PHILIP A. FISCHER.
